MONORAIL CAR AND THE LIKE

Hollis Walter, Baldwin, N. Y., assignor to Sperry Gyroscope Company, Inc., Brooklyn, N. Y., a corporation of New York

Application May 14, 1932. Serial No. 611,309

6 Claims. (Cl. 105—141)

This invention relates to means for stabilizing unstable vehicles, such as mono-rail cars or other automotive vehicles. According to my invention I make use of a gyroscope or gyroscopes for maintaining the stability, but supplement the same with a means for laterally shifting the relative positions of the center of gravity of the car body with respect to the rail or supporting truck so that the car may be maintained in a normally balanced condition. Another object of the invention is to improve upon the type of gyroscopic apparatus heretofore proposed for stabilizing mono-rail cars and the like.

Referring to the drawings showing one form my invention may assume,

Fig. 1 is a vertical section through a mono-rail car body with my invention applied thereto.

Fig. 2 is a horizontal section through one end of the car body, the stabilizing apparatus being shown in plan.

Fig. 3 is a wiring diagram showing the interconnection between the several parts of the apparatus.

Fig. 4 is an end elevation, partly in section, of the mono-rail car shown in Fig. 1.

Fig. 5 is a section through the supporting truck and car body taken at right angles to Fig. 4.

The mono-rail car shown in the drawings is of the double truck variety having trucks 1 and 2 supporting the car body 3 near each end above the single rail 4. Within the car body is mounted the main stabilizing gyroscope 5, said gyroscope being mounted on a vertical spinning axis 6 in a rotor bearing frame 7, which in turn is pivoted on transversely extending trunnions 8 for precession forwardly and backwardly. The trunnions 8 and 8' are shown as journaled in bearings 9 rising from the floor of the car.

It is a well recognized fact that in order to gyroscopically stabilize an unstable object, such as a mono-rail car, that the precession of the gyroscope must be forced or accelerated in order to exert a positive righting torque on the car instead of merely a damping torque such as is exerted by a ship stabilizer. To this end a precession motor 10 is coupled to the gyroscope about its precession axis 8 through gearing 11. Spring applied, magnetically released brakes 12, 12' are shown on the shaft 13 of the motor for quickly stopping the same at the end of each precessional movement. Precession motor 10 is preferably governed by a much smaller control or auxiliary gyroscope 14 which may be mounted in a box 15 near the roof of the car (see Figs. 1 and 3). Said control gyroscope may be of the two degree of free-

dom type and yieldingly centralized by springs 40 about its precession axis 16, or merely a simple or gyro pendulum. On tilting of the car, the first mentioned type of gyroscope will precess against the action of the springs and moves the trolley or brush 17 onto one or the other of the contacts 18, 18', thereby driving the precession motor 10 in the proper direction to accelerate precession and stop the tilting movement and restore the car to its normal position in conjunction with my center of gravity shifting device hereinafter described.

In order to maintain the normal balance of the car and prevent the gyroscope from working over to one side, I provide a means whereby the center of gravity of the car is shifted with respect to the track. Preferably this is accomplished by providing a sliding mount between the car body and truck. As shown, there is mounted across the car body a threaded shaft 21 which is journaled in bearings 22, 22' near the two sides of the car. Said shaft may be rotated from a motor 23 through reduction gearing 24. The motor is preferably placed in circuit with a trolley or brush 25 on the gyroscope 5, which cooperates with fixed contacts 26 and 26' on a frame 9. Motor 23, therefore, is driven in one direction or the other as the gyroscope 5 precesses through more than a predetermined angle (equal to the width of insulated section 41) to either side of its central position. Threaded on shaft 21 is a heavy nut or sleeve 27 which is secured to a plate 28, the bottom portion 28' of which is rounded to form a bolster pin journaled in the top of the truck 1. The bottom frame of the car has a transverse slot 29 therein through which the plate 28 projects, the bottom of the car resting on top of the transversely extending bar 30 resting on top of the truck and forming a shoulder on pin 28'. It will readily be seen, therefore, that upon rotation of the shaft 21 the car body is shifted laterally with respect to the truck along plate 30 and hence the center of gravity is shifted with respect to the single rail 4.

Preferably the reduction gearing 24 and the pitch of the screw 21 are such that the shifting of the body is slow so that only relatively small movements taken place in one direction or the other as the gyroscope precesses back and forth equally on both sides. In case, however, the gyroscope tends to precess more on one side than the other, the car body will be gradually shifted over to correct the balance and equal movements of the gyroscope restored. In Fig. 4 auxiliary supporting blocks 32 and 33 are shown in dotted lines

illustrating how the car may be supported by auxiliary slide rollers 34 and 35 when the gyroscopic apparatus is not running. If desired, laterally shifting means may be provided for each truck 1' and 1' as indicated by the motor 23' and shaft 21' in Figs. 1' and 3.

The advantages of my invention over existing devices become most evident when the vehicle is rounding a curve. In such event the ordinary gyroscopic stabilizer for mono-rail cars will act to hold the car in a vertical position on the curve, thus throwing a much greater load on the gyroscope than would be necessary if the car were inclined toward the center of the curve in accordance with the known laws of banking. In my device, on the other hand, the center of gravity of the car will be automatically shifted on a curve so as to balance the car against the action of centrifugal force. In other words, on a curve the resultant direction of the combined acceleration force of gravity and centrifugal force changes. This causes the gyroscope 5 to precess much more on one side than on the other which results in shifting the center of gravity of the car to correct this condition. My mono-rail device could, therefore, successfully negotiate curves at high speeds without danger and since only one rail or line of road contact is used no banking of the track or road is required.

30. In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use. Thus it is obvious that the same principles as herein outlined may be applied to any bicycle car or vehicle.

45. Having described my invention, what I claim and desire to secure by Letters Patent is:

1. In a mono-rail car, means for shifting laterally the center of gravity thereof with respect to the rail support, a stabilizing gyroscope mounted on the car for precession upon tilting of the car, means for accelerating the precession, and

means responsive to a preponderance of precessional movements of said gyroscope to one side or the other for operating said shifting means in a direction to restore equilibrium.

2. In a bicycle car, a stabilizing gyroscope 80 mounted on the car for precession upon tilting of the car, means for accelerating said precession including an auxiliary gyroscope and a precession motor connected to said stabilizing gyroscope and governed by said auxiliary gyroscope and means for shifting the center of gravity of said car with reference to its support controlled by one of said gyroscopes.

3. In a bicycle car, a stabilizing gyroscope mounted on the car for precession upon tilting of the car, means for accelerating said precession including a control gyroscope and a precession motor connected to said stabilizing gyroscope and governed by said control gyroscope, and means responsive to a preponderance of precessional movement of said stabilizing gyroscope in one direction for shifting the center of gravity of the car to restore equilibrium.

4. In a mono-rail car, a mono-rail truck, a car body adapted to be supported thereon, and 100 means responsive to tilting of said body for shifting it laterally with respect to said truck to maintain the center of gravity thereof directly above the rail.

5. In a bicycle vehicle, the combination with 105 the car body and truck, of means for shifting laterally said body with respect to said truck, a stabilizing gyroscope on said body, and means responsive to unequal precession of said gyroscope to each side of its normal or centralized 110 position for actuating said shifting means to maintain equilibrium and synchronism between said gyroscope and vehicle.

6. In a bicycle vehicle, the combination with 115 the car body and truck, of means for shifting laterally said body with respect to said truck, a stabilizing gyroscope on said body, an auxiliary gyroscope for accelerating the precession of the stabilizing gyroscope upon tilting of the vehicle, and means responsive to unequal precession of 120 said stabilizing gyroscope to each side of its normal or centralized position for actuating said shifting means to maintain equilibrium and synchronism between said gyroscope and vehicle.
